UNITED STATES PATENT OFFICE.

ASHBELL WILLARD BARNUM, OF BENTON, ILLINOIS.

SAFETY PICK-HANDLE.

1,248,993.

Specification of Letters Patent.

Patented Dec. 4, 1917.

Application filed September 8, 1917. Serial No. 190,370.

To all whom it may concern:

Be it known that I, ASHBELL WILLARD BARNUM, a citizen of the United States, residing at Benton, in the county of Franklin, 5 State of Illinois, have invented a new and useful Safety Pick-Handle; and I do hereby declare the following to be a full, clear, and exact description of the invention, such as will enable others skilled in the art to 10 which it appertains to make and use the same.

The present invention relates to a handle fastening means for picks and like tools, and has for its object to provide a device of this 15 character which will enable the head of a pick to be securely fastened upon the handle so that there will be no danger of the pick becoming accidentally disengaged from the handle when in use.

20 Further objects of the invention are to provide a device of this character which is comparatively simple and inexpensive in its construction, which can be readily placed in position or removed therefrom, which will 25 hold the head of a pick securely in position upon the handle, and which will shield and protect those portions of the handle adjacent the head of the pick in such a manner as to greatly prolong the life of the handle.

30 With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

40 Figure 1 is a side elevation of a pick provided with a handle fastening means constructed in accordance with the invention.

Fig. 2 is a top plan view of the same.

45 Fig. 3 is a detail perspective view of one of the sheet metal retaining strips, portions being broken away and shown in section.

Fig. 4 is an enlarged transverse sectional view on the line 4—4 of Fig. 1.

50 Corresponding and like parts are referred to in the following description and indicated in all the views of the drawings by the same reference characters.

Referring to the drawings, which illustrate one possible embodiment of the invention, the numeral 1 designates a wooden

pick handle, and 2 a pick head which is socketed at the middle thereof for the reception of the pick handle. The handle 1 is preferably elliptical in cross section, as indicated more clearly by Fig. 4, and a pair of longitudinally extending retaining strips 3 and 4 applied to the edge portions of the handle at that end thereof which is engaged by the pick head 2. These retaining plates 65 3 and 4 are curved transversely to correspond to the contour of the pick handle and fit snugly against the same, said strips extending through the socket of the pick head and each terminating at its outer end in a 70 pair of laterally projecting wings 5 which engage the front of the pick head. The back of the pick head is engaged by spring shoulders 6 which are formed by stamping tongues in intermediate portions of the retaining strips and curving them outwardly. 75

The retaining strip 4 may be formed with teeth 7 arranged to bite into the handle 1, a pair of opposed straps 8 being provided at the rear end of the retaining strip, said 80 straps extending around the handle and other retaining strip 3 and terminating at the top of the pick handle in ears 8^a which are connected by a clamping bolt 9. When this bolt is tightened the straps 8 are drawn 85 tightly around the pick handle and strip 3, thereby clamping the parts firmly in position and causing the teeth 7 of the strip 4 to bite into the handle.

These straps 8 are formed with longitudinally extending slots 10 which receive outstanding lugs 11 projecting laterally from the edges of the strip 3. An interlocking connection is thus produced between the two retaining strips 3 and 4 which prevents either 90 of them from moving independently of the other when they are assembled in operative position upon the handle and the clamping bolt 9 tightened. The teeth 7 of the strip 4 bite into the handle so that longitudinal 95 movement of the strips upon the handle is impossible, and the pick head 2 is retained firmly in position between the lateral wings 5 and the shoulders 6 so that there is no danger of the pick head becoming accidentally disengaged from the handle when in use. However, if it is desired to remove the pick head from the handle it is merely necessary to take out the clamping bolt 9 and spring the inner ends of the strips 100 3 and 4 apart sufficiently to disengage the teeth 7 from the wooden handle, where-

upon the latter can be withdrawn from position, leaving the retaining strips still within the socket of the pick head. In order to place a pick head upon a handle the steps of the above described operation are merely reversed. When the pick head is in position it is held in such a manner that it cannot become accidentally disengaged from the pick handle, and the strips 3 and 4 serve as shields for those portions of the handle operated adjacent to the pick head, thereby preventing the handle from being splintered or shattered by being brought repeatedly into contact with the material or objects upon which the pick is being employed. If desired, one of the members may be provided with a perforation 12 for the purpose of enabling a tag to be readily attached to the pick when it is sent to the shop for sharpening or repairs. Each workman will thus be enabled to have his proper pick returned to him without any delay or confusion.

Having thus described the invention, what I claim as new and desire to secure by Letters Patent, is:—

1. The combination with a socketed tool head and a handle insertible within the socket, of longitudinally extending retaining strips applied to opposite sides of the handle and extending through the socket of the tool head, said strips being provided at their outer extremities with lateral wings which engage the front of the tool head and one of the strips being provided at its inner end portion with teeth adapted to bite into the handle and also with opposed straps arranged to extend around the handle and other strip, and a clamping bolt connecting the ends of the straps.

2. The combination with a socketed tool head and a handle insertible within the socket, of longitudinally extending retain-

ing strips applied to opposite sides of the handle and extending through the socket of the tool head, said retaining strips terminating at their outer extremities in lateral wings which engage the front of the tool head and the inner end portion of one of the strips being provided with lateral lugs while the inner end portion of the other strip is provided with teeth adapted to bite into the handle and also with complementary straps adapted to extend around the handle and first mentioned strip, said straps being slotted to receive the lugs of the first mentioned strip, and a clamping bolt connecting the ends of the straps.

3. The combination with a socketed tool head and a handle insertible through the socket, of longitudinally extending retaining strips applied to opposite sides of the handle and extending through the socket of the tool head, the outer ends of the strips terminating in lateral wings which engage the front of the tool head while intermediate portions of the strips are provided with shoulders for engagement with the back of the tool head, the inner end portion of one strip being provided with lateral lugs and the inner end portion of the other strip being provided with teeth adapted to bite into the handle and also with complementary strap members arranged to extend around the handle and first mentioned strip, said strap members being slotted to receive the lugs of the first mentioned strip, and a clamping bolt connecting the ends of the strap members.

In testimony whereof I have signed my name to this specification in the presence of two subscribing witnesses.

ASHBELL WILLARD BARNUM.
